UNITED STATES PATENT OFFICE

JOHN ROWLAND NOCK AND CECIL JOHN NOCK, OF BROOKLYN, NEW YORK

PHONOGRAPH STARTING AND STOPPING DEVICE

Application filed May 26, 1928. Serial No. 280,755.

This invention relates to phonograph starting and stopping devices and in particular to one in which few working parts are necessary.

5 A particular object of the invention is to provide a device which will be operated automatically, not only to stop the phonograph turn-table when the tone arm has reached the end of the selection but will be also operable automatically to permit the starting of the turn-table when the tone arm has been swung to a point adjacent the outer periphery thereof, or in position to start the playing of the record.

10 15 A still further object of the invention is to provide in connection with the tone arm, a starting and stopping control device which will be operated by the movement of the tone arm.

20 25 To enable others skilled in the art to fully comprehend the underlying features of our invention that they may embody the same in the various modifications in structure and relation contemplated, a drawing depicting a preferred form has been annexed as a part of this disclosure and in such drawing, similar reference characters denote corresponding parts throughout all the views, of which,

30 35 Figure 1 is a top plan view of an automatic starting and stopping device shown in position adjacent the turn-table of a phonograph, a fragment of the turn-table and part of the tone arm in one position being shown in outline and several of the operating positions of the device being also shown in outline.

40 Figure 2 is a section taken on the line 2—2 of Figure 1 and illustrates how the device is secured to the upright portion of the tone arm and in position to underlie the turntable, and

45 50 Figure 3 is a section taken on the line 3—3 of Figure 2 to show how the operating arm pin is moved by the operating arm to throw the pad against the down turned flange of the turn-table.

Referring to the drawings in detail, 5 indicates a tone arm base which is mounted on the top surface of the phonograph 6, in the usual manner, and is arranged to hold in

pivotal position, the tone arm 7. This tone arm is provided with a vertical portion and a horizontal portion 8, the latter of which at its outer extremity carries the reproducing unit 9, which, as is well known, carries the record engaging needle.

The turn-table which carries the record, is indicated by the numeral 10 and is provided with a depending edge flange 11, against the inner surface of which, is arranged to contact, the brake pad 12. This pad 12 is carried on the end of the stop lever 13 which is connected through the medium of the spring 14 with a pin 15 secured in the base plate 16, the base plate 16 being fastened to the phonograph top 6 in position to permit the free swinging movement of the stop lever 13 so that the pad 12 can be moved out of and into contact with the flange 11 of the turn-table 10. This stop lever is pivoted to the base plate as at 17 and is provided with an extended arm portion 18, the latter of which is also provided with a pin 19 which engages within a slot 20 of an elongated character provided in the control arm 21. This control arm is pivoted at one of its ends as at 22 to the outer end of the carrying arm 23, which arm, in turn, is secured as at 24 to the flange portion 25 of the upright part of the tone arm 7.

It is quite evident that the arm 23 will have swinging movement with the tone arm and due to the pivotal connection of the arms 21 and 23, both of them may assume the position illustrated in outline at the left in Figure 1. This outline position of each of the arms 21 and 23 in this instance coincides with that of the tone arm which is also shown in outline and is in the reset position and the swinging movement of the arm 23 has drawn upon the arm 21 to pull on the pin 19 with the result that the stop lever 13 is thrown from its full line to its dotted line position because the spring 14 will pass the pivotal center 17 of the lever 13 and will cause the lever to snap to the position shown in outline in Figure 1. At this time the record starts playing because the stop or brake pad 12 has been removed from its contact with the flange 11 of the turn-table and the tone

arm travels across the face of the record. When the needle has reached the last groove and the playing of the record has been completed, the parts will be in the position illustrated in full lines in Figure 1, that is, the arms 21 and 23 will have assumed positions whereby the pin 19 will have been engaged by the end 26 of the adjusting screw 27 and will have been moved to a position where the 10 spring 14 will be on the opposite side of the pivotal pin 17 and will consequently throw the pad 12 into contact with the flange 11 of the turn-table.

In order that the throw of the lever 13 15 may be controlled, the adjusting screw 27, which is provided with a knurled thumb nut 28 and is threaded throughout its length has adjustable movement through an upturned lip 29 formed on the arm 21, the extreme 20 end of the adjusting screw 27 being provided with a reduced portion 30 and a peened over head 31 which maintains in position on the end of the screw, the guide 32. The lower end of the guide is turned over to provide a 25 foot 33 which is disposed in the slot 20 of the arm 21, and consequently, the foot 33 will engage the pin 19 carried by the stop lever 13 and depending upon its adjusted position, will cause the throw of the arm 13 to cause 30 the pad to contact with the flanged edge of the turn-table. One of the intermediate positions of the arms 21 and 23 is also shown in outline position in Figure 1.

It is quite evident that in the playing of a 35 record embodying a short selection, it would be necessary to advance the adjusting screw 27 to a point where it would operate the stop lever 13 more quickly than in the playing of a record where the selection was of greater 40 length.

It will be especially noted that the spring 14 is connected in such a manner to the stop lever 13 that it will be double acting, that is, it will have a tendency when the lever is 45 thrown to a position so that the spring 14 passes over the pivot point 17, to draw the pad 12 and snap it in the position shown in outline, while in its opposite movement, it will have a tendency to urge the pad 12 into 50 contact with the flange of the turn-table.

It is evident, therefore, that we have provided a phonograph turn-table starting and stopping device which comprises few parts, which may be readily positioned on any 55 phonograph and which will do away with the necessity of having to manually stop the turn-table at the end of each selection.

It will be noted, also, that instead of riveting the end of the arm 23 to the tone arm, 60 the same may be fastened with a suitable gripping clamp so that it can be removed or replaced at will.

It is evident, also, that our improved device is adaptable for use in connection with 65 any phonograph employing a tone arm and

the entire mechanism will be substantially concealed by the turn-table and will not interfere with the efficient operation thereof.

While we have illustrated and described our invention with some degree of particularity, we realize that in practice various alterations therein may be made. We therefore reserve the right and privilege of changing the form of the details of construction or otherwise altering the arrangement of the correlated parts without departing from the spirit of the invention or the scope of the appended claims.

Having thus described our invention, what we claim as new and desire to secure by 80 United States Letters Patent is:—

1. The combination with a phonograph having a record carrying turn-table and a tone arm movable thereover, of a base plate secured beneath said turn-table, a lever pivoted thereto, a spring connecting the lever and the base plate and arranged to move across the pivot point to urge the lever toward or away from the edge of the turn-table and an arm carried by the tone arm for controlling the movements of said lever.

2. The combination with a phonograph having a record carrying turn-table and a tone arm movable thereover, of a base plate secured beneath said turn-table, a lever pivoted thereto and arranged to engage a down-turned edge of the turn-table, a spring connecting the lever and the base plate and arranged to move across the pivot point to urge the lever toward or away from the edge of the turn-table, an extension on the tone arm, an operating arm pivoted thereto, and a pin and slot connection between the operating arm and said lever.

3. The combination with a phonograph having a record carrying turn-table and a tone arm movable thereover, of a base plate secured beneath said turn-table, a lever pivoted thereto, a spring connecting the lever and the base plate and arranged to move across the pivot point to urge the lever toward or away from the edge of the turn-table, a pin on the end of the lever, an extension on the tone arm, a slotted operating arm pivoted thereto, the slot receiving the pin and permitting movement thereof longitudinally of said arm, and an adjustable member in said slot for limiting the movement of said pin.

4. The combination with a phonograph having a record carrying turn-table and a tone arm movable thereover of a base plate secured beneath said turn-table, a lever pivoted thereto, a spring connecting the lever and the base plate and arranged to move across the pivot point to urge the lever toward or away from the edge of the turn-table, a pin on the lever, an extension on the tone arm, a slotted operating arm pivoted thereto, said slot being arranged to receive the pin, whereby the arm may have move- 136

ment relatively to the lever to cause throw of the same into starting and stopping positions, an adjusting screw on the arm and a traveller in the slot carried on the end of said screw for controlling the operation of the starting and stopping lever.

5 In testimony whereof we affix our signatures.

JOHN R. NOCK. [L. S.]
